FLUID BREAK CIRCUIT INTERRUPTER

Filed July 9, 1930

Fig. 2.

Inventor:

William K. Rankin,
by Charles T. Muller
His Attorney.

UNITED STATES PATENT OFFICE

WILLIAM K. RANKIN, OF LANSDOWNE, PENNSYLVANIA, ASSIGNOR TO GENERAL ELECTRIC COMPANY, A CORPORATION OF NEW YORK

FLUID-BREAK CIRCUIT INTERRUPTER

Application filed July 9, 1930. Serial No. 466,641.

My invention relates to fluid-breaker circuit interrupters and more particularly to interrupters of the expulsion or so-called explosion chamber type wherein the pressure generated by the arc is effective to force insulating liquid across the contact surface of one or both of the coating contacts.

It is an object of my invention to provide an improved fluid-break circuit interrupter of the expulsion type which shall be efficient in operation and simple and rugged in construction.

It is a further object of my invention to provide an improved expansion and separating chamber for the oil and gases ejected from the main oil chamber or casing of an expulsion type oil circuit breaker.

Another object of my invention is to provide an improved insulating mounting structure for a high tension, high capacity fluid break circuit interrupter of the aforesaid type.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view, partly in section, of a circuit interrupter embodying my invention and Fig. 2 is a fragmentary cross sectional view taken along the line 2-2 of Fig. 1.

The circuit interrupter illustrated in Fig. 1 comprises the relatively movable contacts 1 and 2 adapted to engage and disengage within an insulating liquid 3 contained within a sleeve-like cylindrical insulating casing

4. The casing 4 is partially closed by a plate 5 suitably mounted thereon at its lower end and is open at its other end and in communication with an expansion and separating chamber 6. The chamber 6 is mounted upon

an annular conducting member 7 to which the upper part of the casing 4 is suitably secured and has mounted at its lower part a spider, or the like, 8 providing the mounting structure for the stationary contact 1. The

openings in the spider 8 accordingly permit expulsion of the oil or other insulating liquid together with gas past the stationary contact and into the expansion chamber where the gas is separated from the liquid and may exhaust by way of the vent 9 through the

pebble separating chamber 10. Accordingly the oil or other insulating liquid is not lost and flows by gravity back into the casing 4. The expansion chamber 6 may likewise be provided with an emergency exhaust vent 60 such as the concavo-convex disc 11 adapted to be blown through the opening 12 at the upper part of the casing in response to excessive pressure therein.

The stationary contact 1 is mounted adjacent the upper end of the casing 4 and comprises a cylindrical retaining structure 13 integrally secured to the spider 8 and a vertically movable contact member 14 provided with a stop shoulder 15 and normally 70 biased, as by a spring 15', to the lower position illustrated in Fig. 1. The contact member 14 is circumferentially engaged by a plurality of spring pressed contact segments 16 electrically connecting the contact member 75 to the contact retainer which is in turn electrically connected through the member 7 to one of the switch terminals 17.

The movable contact 2 comprises a rod-like member having a blunt or rounded end 80 adapted to make contact with the correspondingly shaped contact surface at the lower end of the contact member 14 of the stationary contact 1. In the upper closed circuit position of the contact rod, it is engaged by the contact segments 16, the contacting surfaces being below the oil level.

For the purposes of guiding and operating the movable contact rod for vertical movement within the casing, there is provided a 90 guide member 18 and a rack and pinion operator 19-20 as best illustrated in Fig. 2. The guide 18 likewise makes sliding electrical contact with the contact rod 2 and is mounted transversely of and in conducting relation 95 with a depending housing 21 having a lower extension for the contact rod and provided with a terminal member 21'. The pinion 20 is secured to a shaft 22 suitably journaled in the casing 21 through a fluid-tight seal 22' 100 and is operatively connected to its actuating means (not shown) through an insulating conduit 23.

The insulating and mounting structure for the breaker comprises a pair of hollow insulating members 24 and 25 between which is disposed a fixed support 26 having a central opening in registry with the insulating members, and in abutting engagement therewith. The support 26 is mounted upon a pair of 110

angle members 27 which may also support a plurality of similar units in a polyphase system. The insulating members are suitably secured to the fixed support 26 as by the 5 annular flanged members 28 to which the insulators are united by cement, or the like. The insulating structure above described is of well known ceramic material for insulating conducting portions at high voltages and is 10 much stronger under compression than under tension.

For the purpose of mounting the inner casing 4 with respect to the supporting insulating structure so that only compression 15 stresses are set up in the comparatively brittle insulating material, the casing 4 is provided with means hereinafter described for engaging the opposite outer ends of the insulating structure. The cylindrical casing 4 is also 20 provided with an inner insulating lining 29 of material highly resistant to arcing and insulating spacers 30 are disposed between the lining 29 and the casing 4 to prevent fracture of the lining by internal pressure. Secured 25 to the upper end of the casing 4 is a flange 31 forming part of the member 7 which is in abutting engagement with and resiliently mounted on, as by the yielding gasket 32, the upper part of the insulating member 24. The 30 lower part of the casing 4 has secured thereto the centering plate 5 upon which is mounted the guide cylinder 33 for the contact rod. The plate 5 is also provided with an offset flange 34 abutting a spacing ring 35 at the 35 lower part of the insulator 25. The outer ends of the insulators 24 and 25 have united thereto as by cement the annular flanged members 36 and 37 for clamping the spacing rings 35 in position, the member 37 having 40 bolted or otherwise secured thereto the depending housing 21 for closing and sealing the lower part of the casing 4.

The inner casing 4 and its associated elements comprise a unit having a resilient mounting with respect to the outer insulating structure which is mounted between the member 7 and plate 5. It will be noted, therefore, that the casing 4, regardless of the direction of the reactive force during the current interruption, can transmit only compressive forces to the supporting insulators 24 and 25. For example, if the casing 4 is subjected to a downward force during expulsion of oil therefrom, the insulator 24 is placed under 55 compression whereas insulator 25 is under no stress since it is merely in abutting relation with the spacing ring 35. The insulators are, therefore, not subjected to tension and are less liable to failure. The insulating 60 casing 4 may likewise be provided with reinforcing bands 38 at its opposite ends so that the casing, which is subject to expansive forces and is under hoop tension, may safely withstand the forces generated by the 65 arc. An annular space 39 separates the cas-

ing 4 from the insulators 24 and 25, this space being in communication with atmosphere through a vent 40 in the event of an increase of pressure therein.

When the circuit breaker is to be actuated 70 from the open circuit position illustrated in Fig. 1 to the closed circuit position, the pinion 20 is rotated by its actuating means to cause upward movement of the contact rod 2 through the oil and into abutting engagement with the lower end of the contact member 14. The operating rod overtravels its initial engagement so as to contact with the contact segments 16 and compress the spring 15' thereby obtaining good contacting engagement. The switch opening operation is effected by rotating the pinion 20 in the opposite direction and rapidly moving the contact rod downwardly out of engagement with the fixed contact and through the oil. The 80 following engagement of the member 14 during the initial part of the opening movement causes the arc to be formed between the separating contacts at the tip or blunt end of the contact rod and the coacting end of the member 14, and possibly at the lower portion of the retainer 13, thereby limiting the arcing to surfaces not normally carrying the main current.

The intense heat of an arc drawn within 90 an insulating liquid such as oil, generates, as is well known, quantities of gases at a high rate so as to greatly increase the immediate pressure. In the present instance, the formation of the arc tends to blast or expel the oil 100 and gas at high velocity from the upper part of the casing 4 due to the sleeve-like proportions thereof, past the contact 1 and upwardly into the expansion chamber 6 where the gas is partly cooled by passage through 105 the pebble separating chamber 10 and exhausted exteriorly of the chamber by way of vent 9. The oil, separated from the gas and remaining within the chamber, may thereafter flow back into the casing 4. As 110 the contact rod continues to move downwardly within the oil it is covered by fresh dielectric which tends to cool the arc at that point. In the event that the circuit is not at once cleared, continuation and lengthening of the arc as the contact rod moves downwardly, causes more oil to be expelled from the casing past and across the arcing surfaces of the contact 1 and into the expansion chamber so as to carry away the arc products and 120 to extinguish the arc. In certain instances it may be desirable to direct the ejected oil in a particular manner into the arc stream or to increase the expulsion effect of the arc. For this purpose the casing 4 may be 125 provided with insulating baffles or barriers of well known construction arranged along the path of the arc.

It shall be understood that my invention is not limited to specific details of construc- 130

tion and arrangement thereof herein illustrated, and that changes and modifications may occur to one skilled in the art without departing from the spirit of my invention.

5 What I claim as new and desire to secure by Letters Patent in the United States is:

1. A circuit interrupter comprising a pair of hollow insulating members, a fixed support for said interrupter intermediate and abutting said members, a cylindrical casing containing an insulating liquid disposed within and concentrically of said insulating members, and coacting contacts adapted to separate and draw an arc within said insulating liquid, said casing including means having abutting engagement with the opposite ends of said insulating members so that compressive forces only are transmitted to said insulating members during circuit interruption.
2. A high tension, high capacity circuit interrupter comprising a hollow insulating structure, a fixed support for said interrupter rigidly secured to said structure, a cylindrical casing containing insulating liquid disposed within and concentrically of said hollow insulating structure, and relatively movable contacts adapted to separate and draw an arc within said liquid, said cylindrical casing provided with flanged members at opposite ends thereof between which the

corresponding ends of said insulating structure are mounted in abutting engagement so that said insulating structure is under compression between said casing and said fixed support due to explosive pressures generated within the casing during circuit interruption. 70

3. An oil circuit breaker of the expulsion type comprising a vertically mounted cylindrical casing containing oil, said casing being restricted in cross section as compared with its length, a stationary contact immersed in said oil disposed centrally of and within the upper end of said casing, a rod contact coacting therewith and movable vertically through the oil within said casing so that an arc drawn between said contacts within the oil is effective to eject oil and the resulting arc gases through the arc and from the upper end of said casing, and an expansion and separating chamber disposed above and freely communicating with said casing for receiving oil and gases during circuit interruption, said chamber being provided with a separating chamber and vent for venting said gases exteriorly of the chamber and permitting return of the oil to said casing. 80 85 90

In witness whereof, I have hereunto set my hand this 7th day of July, 1930.
